Dec. 1833

R. Wheeler and S. A. Bailey, Utica, N. Y.
Letters Patent No. 1833 dated Oct. 15, 1833.

Design for a Cooking Stove

The schedule referred to in these Letters Patent and making part of the same

To all whom it may concern:

Be it known that we Russell Wheeler and Stephen A. Bailey, of the City of Utica, in the County of Oneida, and State of New York, have invented a new and improved design for a cook stove; and we do hereby declare that the following is a full and exact description thereof, reference being had to the accompanying drawings.

The nature of our invention consists in a new design for a cook stove, as represented in the accompanying drawings.

To enable others skilled in the art to make and use our invention, we will proceed to describe its design and construction.

The stove proper is of cast iron, and the upper plate is designated by the letter A. The mouldings around the hearth, doors, and base are respectively designated by the letters B, D and C, and the ornaments on the doors are all of the same form, and are designated by the letter E, on the accompanying drawings.

What we claim as our invention and design, and desire to secure by Letters Patent, are the forms and ornaments constituting a design of a cook stove, as above described and represented.

Witnesses:

M. W. Jones,
Wm Richardson.
